UNITED STATES PATENT OFFICE.

WILLIAM V. D. KELLEY, OF NEWARK, NEW JERSEY, ASSIGNOR TO PRIZMA, INCORPORATED, OF JERSEY CITY, NEW JERSEY, A CORPORATION OF MAINE.

COLOR TRANSPARENCY.

Application filed August 25, 1920. Serial No. 405,787.

To all whom it may concern:

Be it known that WILLIAM V. D. KELLEY, a citizen of the United States, and a resident of Newark, in the county of Essex and State 5 of New Jersey, has invented certain new and useful Improvement in Color Transparencies, of which the following is a specification.

This invention relates to motion pictures 10 in color and has for its object to provide a simplified process whereby colored pictures may be produced from ordinary black and white value negatives as well as from color value negatives.

15 It is found that very pleasing color effects can be produced by printing from a single negative at a single operation in both coatings of a multiple coating positive and then after development and fixing in the ordinary 20 manner applying one color to one coating and another color to the other coating. The resulting pictures do not substantially reproduce natural color, but do produce very 25 pleasing effects, and are found especially useful for titles in natural color motion picture films as well as for toned effects in black and white films wherein the resultant color is subtractively produced by the different 30 colors on the respective images. If the tone colors used are, for example, red and green, predominant red effects are produced by over-balancing either the printing of the image to be colored red, or the tone coloring bath, and likewise with green or whatever 35 colors are used. It is found that ordinary double coated positive or transparent stock is admirably suited for this process because in a single printing operation from one side a relatively strong positive image will be 40 produced in the coating adjacent the negative, and a relatively weaker image in the coating on the other side, giving sufficient opacity to produce approximations to black and sufficient white to produce approximations 45 to white with variations of intermediate colors, depending upon the amount of color fixed in the positive images. Very pleasing effects can also be obtained by leaving one image in black and coloring the 50 other image with red, since in projection it is found that the eye will supply partial sensations of green, resulting in a picture resembling a natural color picture in whites and blacks and intermediate colors, but not a 55 true natural color picture because not made

from color value images and not colored with complementary red and green.

This process furnishes a cheap and simple way of producing one or more color toned transparencies capable of being made from 60 ordinary black and white value negatives, and in many instances satisfactorily replacing color value negatives and natural color positives, without the expense of initially 65 making color value negatives, and without employing the separate printing and complementary toning steps ordinarily required in producing natural color pictures.

The invention is shown diagrammatically in the accompanying drawing, wherein— 70

Figure 1 is a view of a negative.

Figure 2 a single printing operation,

Figure 3 a view of one side of the positive with the image colored red,

Figure 4 the other side of the positive 75 with the image colored green,

Figure 5 a section of the finished positive.

Fig. 6 shows the printing method for an image containing an intermediate or gray portion, and 80

Fig. 7 shows the print.

1 represents a portion of an ordinary negative having the image 2, 3 represents a section of transparent stock having an emulsion 4 on one side and 5 on the other, to be 85 printed at a single operation, as shown in Figure 2, to produce the positive image 6 on one side, to be colored red, as shown in Figure 3, and the second positive image 7 on the other side, to be colored green, as shown in 90 Figure 4.

In Fig. 6, 8 is an intermediate or gray portion of the negative, and in Fig. 7, 9 is the positive of this portion colored red and lighter than the red section 6, while 10 is the 95 print on the other side colored green, and lighter than the portion 7.

The effects to be produced vary according to the exposure and color, both of which can of course be regulated in manufacture. If 100 over-exposed and then over-colored, heavy black, or almost black, images result, but if properly exposed, the whites in the object come out white in the positive and the blacks come out substantially black, while intermediate colors vary between red and green, according to the intensity of coloring.

For coloring, the ordinary metallic toning baths can be used wherein the color is formed by a metallic precipitate, or the posi- 110

tive images can be bleached and dyed by acid or basic dyes in a known manner, or one image can be left in black and the other dyed or toned as with red, which in projection will appear to contain green, or colors containing green, although not in fact having any green therein.

By this invention a color transparency suitable for titles, backgrounds, scenery, portraiture, etc., can be cheaply made from ordinary black and white or color value negatives and giving a much wider range of color, owing to the possibility of using two colors than is possible with single color toner positives commonly used.

What I claim is:-

1. Process of making a color transparency consisting in printing from a single negative in one operation images in different layers

of multiple layer positive, developing both images, and coloring one image in one color and the other in a contrasting color.

2. Process of making a color transparency consisting in printing from a single black and white value negative in one operation images in different layers of multiple layer positive, developing both images, and coloring said images in contrasting colors.

3. A double coated positive transparency having on each side a black and white value image, one of said images being colored in one color and the other in a contrasting color to produce a double toned black and white value color transparency.

Signed at Atlantic City in the county of Atlantic and State of New Jersey this 20th day of August A. D. 1920.

WILLIAM V. D. KELLEY.
